BRAKE OPERATING MECHANISM

Edward Brian Wilson, Westminster, London, England, assignor to Wilson Box (Foreign Rights) Limited, London, England

Application May 31, 1933, Serial No. 673,783
In Great Britain June 6, 1932

1 Claim. (Cl. 188—77)

This invention relates to improvements in or in connection with gear-changing mechanism of the type wherein reaction members are held stationary by means of brakes.

In epicyclic change speed gearing, it is not only desirable that no additional load should be placed upon the shafts or bearings upon the application of any brake to its reaction drum, but also that a self-intensifying effect by lapping or wrapping of the brake strap around the drum should tend to be produced. As the reaction drums for forward and reverse gears tend to rotate in different directions, it is clear that the straps designed to hold them stationary will not both tend to "wrap" if tensioned in the same direction.

In mechanism of this type, as illustrated and described in British patent specification No. 220,021 granted to Walter Gordon Wilson, the brakes for the forward gears tend to lap in the one direction, and as it is desirable that all the brakes, both for the forward and reverse gears, should be actuated by a common means, a mechanism is described and illustrated in United States Patent No. 1,915,706 granted to Walter Gordon Wilson, whereby, by means of the employment of certain additional parts, lapping in the contrary direction is brought about in connection with the brake controlling the reaction drum for the reverse gear.

The object of the present invention is to provide a simpler means, whereby the strap for holding the reaction drum for the reverse gear tends to wrap in the required direction, while the actuating means is adapted to be operated by a common member, and at the same time no extra load is thrown upon the shafts or bearings, and the proper selection of the desired gear is assured.

The invention consists in a brake operating mechanism for the reverse speed of an epicyclic change speed gear, comprising a pair of brake bands surrounding the brake drum and superimposed one upon the other, the ends of the inner band being disposed on the opposite side of the drum to those of the outer band, a link pivoted at one end to one end of the inner band and at its other end secured to the gear box, a pull rod secured to one end of the outer band, a finger secured at one end to the gear box and at its other end pivotally supporting the said pull rod, a toggle lever pivotally connected to the said finger and engaging the free end of the outer band, a strut pivotally connected to the said toggle lever and a rocking bus bar supporting the said strut. The arrangement is such that when the bus bar is raised the free end of the outer band is

pulled on to the brake drum in the direction of rotation of the latter, which rotation is opposite to that of the forward speed groups.

The invention will now be described with reference to the accompanying drawing, in which:—

Figure 1 is a front elevation of the brake element and its associated operating mechanism for the reverse gear, in the "off" position,

Figure 2, a view similar to Figure 1, showing the operating mechanism in the "on" position, 10

Figure 3 a section through the brake bands taken on the line 3—3 of Figure 1, and

Figure 4, a view similar to Figure 3, showing an alternative arrangement of brake bands.

Figure 5 is a side elevation of the brake. 15

In carrying the invention into effect, the brake element for the reversing drum comprises a brake band 1 which extends around the brake drum 2, and forms a secondary brake element. Superimposed upon the brake band 1 is a band brake 3 which forms the primary brake element and is so arranged as to contact across half its width with the brake drum, thus constituting a direct brake (see Figure 3). It is to be understood that, although in the preferred arrangement of the 20 brake element only one secondary brake band 1 is used, two such brake bands, disposed side by side as shown in Figure 4, could be included if necessary. Each band has its own brake lining 25 of asbestos or other similar material, and is arranged so that its two ends are relatively near to one another, the respective ends of one band being displaced substantially 180° to those of the other band, so as to be on opposite sides of the 30 centre of the drum.

One end of the primary brake band 3 is provided with a block 4 pivotally connected at 5 to a toggle lever mechanism, to be hereinafter described, whilst the eye-piece 6 on the other end of the band 3 is pivotally connected at 7 to a pull rod 8. The secondary brake band 1 is attached at one end to a lug 9 which is extended radially through a slot 10 in the primary brake band 3, and extends round the drum 2 following its direction of rotation, that is in a counter-clockwise direction, and is left with a free end at a point just below the lower end of the slot 10. The lug 9 is anchored as by a link 11 pivotally secured at 12 to the base plate 13 of the gear box. 35

The brake operating mechanism comprises the bus bar 14 fulcrumed about the knife edge 15 on the bottom plate 13, which bar supports, by means of a knife edge 16, a strut 17 having pivotally mounted at its upper end 18 a toggle lever 55

19 which is extended to form a hooked end 20 having a knife edge connection 5 with the hooked end 4 of the primary brake band 3. The other end 6 of the said band 3 is pivotally connected 5 at 7 to the pull rod 8, the upper end of which rod is pivotally supported, by means of a knife edge 21, upon a finger 22, which latter is in turn pivotally connected at its upper end to the toggle lever 19 by a knife edge 23, and at its lower end 10 pivotally secured at 24 to the bottom plate 13. The upper end of the pull rod 8 is also provided with an automatic brake adjusting mechanism 26 which is adapted to co-operate with abutment members 27 and 28 in the manner described and 15 illustrated in United States Patent No. 1,854,358, granted to Walter Gordon Wilson, in order to take up any slack that may occur due to wear.

As shown in Figure 1, the brake element and its associated parts are in the inoperative position with the bus bar 14 in its lowermost position. 20 In order to apply the brake, the bus bar 14 which may be operated by the lever and link actuating system described and illustrated in United States Patent No. 1,854,359 granted to Walter Gordon 25 Wilson, is allowed to swing upwardly about its fulcrum 15 (see Figure 2) thereby imparting an upward movement to the strut 17 which causes the toggle lever 19 to swing in a clockwise direction about the fulcrum 23 and exert a downward pressure on the hooked end 4 of the primary brake band 3. This downward pressure causes the primary brake band 3 to be tightened 30 on to the brake drum 2 in the direction of rotation of the latter, viz. counterclockwise direction, 35 the other end 6 of the band being anchored through the pull rod 8 and finger 22.

When such a braking system is relaxed, the 40 brake bands would be free to drop and rub on the top of the drum 2. Any suitable devices may be used to prevent this; for instance, the lower part of the primary band 3 is adapted to be supported at two points upon a pair of stops 29 each pivotally secured at 30 and 31 to the bottom plate 13 and a lug 32 respectively. These parts are

so positioned that when the brake is released, the bands are kept clear equally all round or concentric with the drum.

By means of this invention, a simplified form of brake actuating mechanism is supplied which enables the wrapping effect of the bands to occur in the appropriate directions, while the bands for holding the drums for the forward gears, as well as the reverse, are actuated by the same common member and the brake actuating mechanism is all on the same side of the gear box; the toggle lever fulcrum will always remain in substantially the same position relatively to the centre of the gear system when the brake is not being applied, whatever adjustment may have 15 taken place by reason of the condition of its operative lining, and as the constant position of this point is an essential requirement for the proper functioning of the mechanism, the present invention ensures by simple means the certainty of selection and operation of the whole system, whatever adjustment for wear may have taken place.

Having now described my invention what I claim as new and desire to secure by Letters 20 Patent is:—

Brake operating mechanism for the reverse speed of an epicyclic change speed gear, comprising a pair of brake bands surrounding the 30 brake drum and superimposed one upon the other, the ends of the inner band being disposed on the opposite side of the drum to those of the outer band, a link pivoted at one end to one end of the inner band and at its other end secured to the gear box, a pull rod secured to one end of 35 the outer band, a finger secured at one end to the gear box and at its other end pivotally supporting the said pull rod, a toggle lever pivotally connected to the said finger and engaging the free end of the outer band, a strut pivotally connected to the said toggle lever and a rocking bus bar supporting the said strut.

EDWARD BRIAN WILSON.
